UNITED STATES PATENT OFFICE

2,559,228

ELECTRIC WALL INCINERATOR

Anton H. Riebschlager, Fresno, Calif.

Application November 8, 1947, Serial No. 784,892

2 Claims. (Cl. 219—19)

1

The present invention relates to incinerators and more particularly to wall incinerators directed to the prompt, sanitary, and convenient disposal of combustible material in relatively small quantities.

The problems of sanitary and convenient disposition of disposable tissue are of quite general human experience. These and other problems and inconveniences are encountered in aggravated form in the disposal of catamenial devices. The inconveniences and embarrassment incident to such disposal are of common knowledge and are testified to by the frequent clogging of plumbing in homes, rest rooms, and other places frequented by the public.

An object of the present invention is to alleviate this frequent clogging of plumbing fixtures and drainage pipes by the provision of an improved means for disposing of catamenial devices, disposable tissue, and other combustible material in relatively small quantities.

Another object is to provide an improved compact incinerator adapted to be received between opposite surfaces of a supporting wall, particularly walls of bathrooms, rest rooms, and the like.

Another object is to provide a wall incinerator suited for use in homes, stores, offices, and other buildings as well as trains, buses, and other means of conveyance, which readily admits and consumes disposable tissue and the like in sanitary and convenient manner.

Another object is to provide a convenient, efficient, and sanitary means for disposing of catamenial devices.

Another object is to provide a simple, safe, and effective means adapted to be built into a supporting wall for disposing of combustible material in relatively small quantities.

Other objects and advantages will become apparent in the further description in the specification.

In the drawings:

Fig. 1 is a front view of a device of the present invention shown mounted in a fragmentarily illustrated supporting wall.

Fig. 2 is a perspective view of a device embodying the principles of the present invention, having a face-plate thereof removed to reveal normally concealed features of the present invention.

Fig. 3 is a section taken on line 3—3 of Fig. 2.

Fig. 4 is a side elevation of the device, having a portion of the side wall thereof removed to reveal relationships between internal elements of the incinerator and external elements thereof while said elements are in normal position.

2

Fig. 5 is a fragmentary side elevation of the incinerator illustrating the insertion of catamenial devices into the same.

Fig. 6 is a view similar to Fig. 5 but showing the incinerator closed, the catamenial device positioned therein for dehydration and burning, and relative positioning of elements of the invention at the initiation of said dehydration and burning.

10 Fig. 7 is similar to Figs. 5 and 6 but shows a relationship of elements of the incinerator near the completion of the combustion of the catamenial devices.

15 Fig. 8 is a diagrammatic representation of an electrical circuit employed in the first form of the present invention.

Fig. 9 is a second form of the present invention in which a continuously burning pilot light is employed to dehydrate and ignite combustible material.

20 Fig. 10 is a fragmentary illustration of a supporting wall showing mounted therein a third form of the present invention.

Referring in greater detail to the drawings:

25 In Fig. 1, a supporting wall, in which the device of the present invention is mounted, is indicated generally at 10. The wall preferably has sufficient thickness to receive and conceal the device of the present invention except for portions thereof shown in full line in Fig. 1, and presently more fully described. In its most popular size, the device of the present invention is adapted to be received by a wall of conventional frame building. Such buildings are usually 30 framed with two by four studs, usually 3½ inches thick, and provide sufficient room for the device of the present invention.

35 A substantially erect firebox 11, is shown in Figs. 2, 4, 5, 6, and 7, having a front wall 12, 40 a rear wall 13, and oppositely disposed side walls 14 and 15 respectively. The rear wall and side walls are provided with insulation shields 16 of asbestos or other suitable material. To be received by a wall of a frame building having 3½ inch studs, the overall thickness of the firebox 45 from the front of the front wall to the rear of the insulation of the rear wall is preferably slightly less than 3½ inches. Attention is called to the conventional spacing of studs 18 inches 50 from center to center in walls of typical frame buildings which provides ample space for the firebox of the present invention which may be of any suitable width for the purpose and may be mounted between the studs in spaced relation thereto. Such mounting is conveniently accomplished by means of ears 17 laterally ex-

tended from the lower end portion of the firebox as by screwing or bolting the ears to a transverse brace interconnecting adjacent studs in a supporting wall, such as a fire stop 18 of Fig. 1.

An ash collecting drawer 19 is slideably provided in the lower end portion of the firebox and is preferably of a structure conveniently removed for the dumping of ashes collected therein. The drawer is provided with a handle 20 for purposes of convenience and has a plurality of air openings 21 formed therethrough to feed combustion occurring in the firebox, as will presently be more fully explained.

The upper end portion of the firebox 11 is preferably constricted as at 22 and provided with a vent pipe 23 extending upwardly therefrom for venting to the atmosphere.

A substantially rectangular opening 30 is provided in the front wall 12 of the firebox near the upper end portion thereof. The opening is of a size and shape adapted to receive catamenial devices and smaller articles but not sufficiently large to invite the burning of large quantities of combustible material in the incinerator. The opening is normally closed by means of a door 31 pivotally mounted in the firebox near the upper edge of the opening for pivotal movement inwardly and upwardly of the firebox. The door is preferably provided with flanges 32 extended therefrom and overlaying the front wall inwardly disposed the firebox. The flanges provide improved seating of the door in sealing relation to the opening.

A dehydrating and ignition element 35 is provided in a substantially horizontal position within the firebox at a level below the opening 30 and intermediate said opening and the ash drawer 19. The ignition element conveniently takes the form of an electrical heating element, as shown in Fig. 3. The ignition element is mounted in any convenient manner as by winding a wire of electrical conducting but resisting material on clay cores 36 which preferably are in spaced arrangement so that ashes may readily fall therethrough.

A depressing or follow-up member 38 is pivotally mounted in the firebox as at 39, at a position intermediate the ignition element 35 and the opening 30 for pivotal movement between a position overlaying the ignition element, as shown in Fig. 4, and a substantially erect position adjacent the rear wall 13, as shown in dotted line in Fig. 5. The member 38 functions as a depressing means for urging combustible material downwardly in continuous contact with the ignition element until consumed. The depressing member is preferably formed of arms 40 extended from the pivotal mounting 39 and a transverse element 41 interconnecting the extended end portions of the arms and providing additional weight tending to urge the member downwardly. The depressing member is of an open structure impeding combustion of any combustible material in the incinerator to a minimum extent while urging said material downwardly toward the ignition element. To funnel combustible material downwardly onto the ignition element, flanges 42 are mounted on the side walls 14 and 15 and extended downwardly and inwardly therefrom.

As previously mentioned, the door 31 is pivotally mounted in the firebox near the upper edge of the opening 30 for pivotal movement inwardly and upwardly of the firebox. A handle 43 is provided at the side 14 of the firebox in

controlling relation to the door and other elements of the present invention presently more fully described. Controlled interconnection of the handle and the door 31 is conveniently accomplished by journaling a rod 44 transversely in the firebox adjacent the upper edge of the opening. The door is fixedly mounted on the rod, as shown in Figs. 5, 6, and 7. The handle is mounted in fixed radial relation to the rod intermediate its end portions, as by squaring the rod where it extends beyond the firebox, forming an opening in the handle of complementary configuration to the squared end of the rod, and securing the handle in fitted relation to said end portion of the rod. Thus depressing of the handle serves to open the door and release of the handle results in the closing of the door because of the weight thereof. The handle 43 is outwardly extended from the wall from the mounting 44 and also inwardly extended from said mounting. To the end of providing more positive closing of the door, a helical tension spring 45 is interconnected to the inwardly extended end portion of the handle and a position on the firebox downwardly and forwardly disposed thereto, as at 46. Opening of the door puts the spring under increased pressure which results in a positive closing of the door upon release of the handle and effective sealing of the opening 30.

A translating arm 47 is pivotally mounted on the side wall 14 of the firebox 11 below the handle, as by a pivot bolt 48. The translating arm is provided with a plurality of openings 49 arranged in a pattern longitudinally thereof. The plurality of openings provide adjustable interconnecting of the door 31 and the depressing member 38, as presently more fully described.

The pivotal mounting 39 of the depressing member is extended outwardly through the side wall 14. A switch plate 50 is fixedly mounted on the pivotal mounting 39 to pivot therewith relative to the firebox and thus to maintain constant angular relation with the depressing member 38, as shown in Figs. 4, 5, and 6. A bracket stop 51 is secured to the firebox 11, as by welding, and extended therefrom below the switch plate. The stop functions as a rest for the switch plate and as a stop limiting downward movement of said switch plate. The stop is positioned to limit downward pivotal movement of the switch plate and thus of the depressing member to a position for the member short of contact with the ignition element.

The inner end portion of the handle is preferably bifurcated. A push-pull rod 52 is pivotally connected to the bifurcated end portion of the handle and to the translating arm 47 by being bent outwardly and extended through an opening 49 thereof. The push-pull rod is conveniently maintained in handle and translating arm engagement by means of spring clips 53 engaged in annular grooves formed in its push-pull rod. It will be clearly apparent that cotter keys, screw-threaded means, or other arrangements may be employed to maintain the engagement noted.

The switch plate 50 preferably has a slot 54 formed therein radially related to the pivotal mounting 39. It is apparent in Figs. 2, 4, 5, and 6 that depressing of the handle 43 serves pivotally to elevate the translating arm 47. The pivotal elevation is communicated to the switch plate 50 by means of a T rod 55 upwardly extended through the elongated opening 54 of the switch plate, the cross arm of the T rod underlaying the

switch plate, and pivotal connection of the upper end of the T rod to the translating arm by extension through an opening 49 thereof. The T rod is thus slideably associated with the switch plate providing positive pivotal elevation thereof upon depressing of the handle 43 and permitting the switch plate to return freely and independently to its original position upon release of the handle. The upper end of the T rod is maintained in translating arm engagement as by a 10 spring clip 53, already described.

An electrical switch 57 is mounted longitudinally on the switch plate, as by means of an adjustable bracket 58. The switch is preferably responsive to attitude, a mercury switch of conventional form being admirably suited to the purpose. The switch is adjustably positioned by its bracket 58 to maintain an attitude relative the switch plate 50 causing the switch to close when the depressing member 38, with which its switch plate is pivotally mounted, is elevated, as shown in Fig. 5, and to open, when the depressing member is returned to normal position, as shown in Figs. 4 and 7. The ignition element 35 and the switch 57 are connected in electrical series, as shown in Fig. 8, with any suitable source of electrical energy 59 by means of conducting wires 60. The source of electrical energy may conveniently take the form of an electrical lighting circuit of the building in which the incinerator is mounted. To provide indication of the activated and non-activated conditions of the ignition element, a warning light 61 is wired in electrical series with said ignition element and the switch.

The incinerator of the present invention is given a finished appearance by mounting a facing plate 62 in concealing relation to all of the incinerator except the handle 43, the door 31, the ash drawer 19, which are externally accessible, and the pilot light 61 which is externally visible. The facing plate is preferably secured by cap screws 63 extended therethrough and screw-threadedly engaged to the firebox. To accommodate pivotal movement of the handle, an elongated slot 64 is formed in the facing plate.

Operation

Referring to Figs. 4, 5, 6, and 7 in the sequence given, the operation of the present device is clearly apparent and is briefly summarized as follows:

In Fig. 4 the elements of the incinerator are shown in so-called normal position, the door 31 in sealing relation to the opening 30, the depressing member 38 in its downward position overlying the ignition element 35, and the switch 57 opened by its attitude resulting from the downward positioning of the switch plate 50.

The door 31 is opened by depressing the outwardly extended end portion of the handle 43, as by an operator 65, a catamenial device 66, or other combustible material, is inserted through the opening 38. The depressing of the handle having served to pivot the depressing member upwardly, the incinerator is preconditioned for the reception of the catamenial device for burning by upward pivoting of the member 38 and the activation of the ignition element 35 in response to closing of the switch 57. The upward pivotal movement of the depressing member 38 tips the switch plate upwardly and the switch 57 rearwardly, closing the switch and completing the electrical circuit shown in Fig. 8. As shown in Fig. 6, the catamenial device upon insertion descends in the firebox 11 to the flanges 42 or

even to the ignition element 35 itself. In such positions the catamenial device is in intimate proximity to the ignition element. Upon release of the handle 43, the door 31 is closed by gravity 5 and by urging of the spring 45 and seals the opening 30. Downward pivotal movement of the depressing member is initially precluded by the catamenial device against which it is rested.

The ignition element having been activated as described, is brought to a high temperature. The heat generated by the ignition element causes a convectional current of warm dry air to rise through the firebox 11 and to be exhausted through the vent pipe 23, the openings 21 in the ash drawer 19 admitting fresh air for the feeding of such convectional movement. This movement of warm dry air rapidly dehydrates the catamenial device or any other combustible material that may be positioned in the firebox in a moist condition. Continued activation of the ignition element serves to ignite the catamenial device and to consume the same by combustion, the gases of combustion raising through the firebox also to be exhausted through the vent pipe.

As the catamenial device 66 is burned, the depressing member 38 rested thereon continues to urge it downwardly toward the ignition element, as shown in Fig. 7, assuring a continuous burning action until the device is consumed. Upon completion of the consumption of said catamenial device, the depressing member 38 gravitationally returns to position shown in Fig. 4, pivoting the switch plate 50 downwardly and opening the switch 57. Thus upon completion 30 of its function of consuming the catamenial device, the ignition element is inactivated and no subsequent waste of electrical energy occurs.

Second form of the present invention

A second form of the present invention is shown in Fig. 9 comprising a firebox 70 an ash drawer 71, an inserting opening 72 formed in the firebox, a pivotally mounted door 73 in sealing relation to the opening, a depressing member 74, and other elements duplicating the corresponding elements of the first form of the invention already described and thus at this point not further discussed. In the second form, however, the switch 57 is omitted. For the ignition element 35 shown in the first form of the present invention, a gas pilot light 75 is substituted. The pilot light is connected by a conduit 76 to any suitable source of combustible gas, not shown, and preferably is continuous burning. In this 50 form of the present invention, the operation is the same as that heretofore described but with this exception, the pilot light provides a continuous source of dehydrating and igniting heat and no mechanism for interrupting the same is provided.

When the pilot light 75 is employed, it is found advantageous to provide a grill 77 to support combustible material. The grill is preferably supported in a substantially horizontal position just above the pilot light as by brackets 78 riveted to the firebox 70 or secured thereto in any other suitable manner, as by welding.

Third form

In Fig. 10 a third form of the present invention is illustrated, wherein the incinerator of either the first form or second form, but without an ash drawer, is incorporated in a vent pipe 80 of the type normally employed in venting 75 plumbing fixtures. For clarity of illustration the

vent pipe is shown positioned between adjacent studs 31 and extending from a sewer 32 below a floor 33 upwardly for venting purposes. A firebox 84 of the type previously described is formed in an enlarged section of the vent pipe and is provided with an ignition element either of the type 35 or 75 and elements appurtenant thereto already described. A facing plate 85, similar to facing plate 61, is provided for the third form having an opening 86 formed therein through which a door 87, similar to the doors 31 and 73 already described, is conveniently accessible. A handle 88 is extended from the firebox 84 of a form and arrangement similar to the handle 43 for opening the door and for raising a depressing member, such as 38, already described and not again shown or described at this point. The absence of an ash drawer of the type 19 or 73 is to be noted. The firebox is preferably open at its lower end and ashes resulting from the burning of combustible material in the forebox are permitted to fall downwardly through the lower portion of the vent pipe into the sewer 32 to be carried away by sewage flow therethrough.

The incinerators of the present invention are compact and are conveniently built between opposite surfaces of walls such as those delineating bathrooms, rest rooms, and the like. The incinerators are safe to employ in that they are insulated from adjacent structure and are of a capacity adapted to receive only relatively small quantities of combustible material. The structures are simple but effective in operation. The incinerators provide efficient and sanitary means for disposing of catamenial devices and the like, thus obviating present known embarrassment, inconvenience, and difficulty incident to the disposal thereof. The provision of incinerators of the present invention in the walls of public rest rooms and the like have been found materially to reduce and in many instances completely to eliminate clogging of plumbing fixtures and drains incident to the disposal of such devices therein.

Although I have herein shown and described my invention in what I have conceived to be the most practical and preferred embodiments, it is recognized that departures may be made therefrom within the scope of my invention, which is not to be limited to the details disclosed herein, but is to be accorded the full scope of the claims so as to embrace any and all equivalent devices.

Having described my invention, what I claim as new and desire to secure by Letters Patent is:

1. A wall incinerator comprising a substantially erect firebox built into a supporting wall and insulated therefrom, having an opening accessible from externally of the wall through a wall of the firebox near the upper end portion of said firebox, a door fitted in closing relation to the opening and pivotally mounted in the firebox, a vent for the firebox, an electrical ignition element provided in the lower portion of the firebox, a depressing member pivotally mounted in the firebox at a level between the ignition element and the opening for movement between a position overlaying the ignition element and a substantially erect position adjacent a wall of the firebox, an externally accessible handle pivotally mounted on the firebox in unitary relation with the door for opening and closing the same, an electrical switch operably connected to the depressing member whereby upward pivotal movement of the member closes the

switch and return of the member to original position opens said switch, an energizing circuit for the ignition means including the switch and a source of electrical energy, and lever means interconnecting the handle and the depressing member whereby manipulation of the handle to open the door pivots the depressing member upwardly to receive combustible material between said member and the ignition means closing the switch, and whereby, upon release of the handle, the door is closed and the depressing member is rested upon the combustible material and returned to original position upon consumption of said material.

15. 2. A wall incinerator comprising a substantially erect firebox having a front wall, a rear wall, and side walls interconnecting said front and rear walls in spaced relation adapted to fit between opposite surfaces of a supporting wall and to be concealed thereby, said front wall having an externally accessible opening provided in the upper portion thereof; a door fitted in closing relation to the opening and pivotally mounted on the front wall of the firebox; a spring urging the door into closing relation to the opening; a vent for the firebox; an electrical ignition element provided in the lower end portion of the firebox; an ash tray removably positioned in the firebox below the ignition element; a depressing member mounted on the rear wall of the firebox at a level between the ignition element and the opening in the front wall for pivotal movement between a position overlaying the ignition element and a substantially erect position adjacent the rear wall; stops borne by the firebox limiting downward pivotal movement of the depressing member to a position short of contact with the ignition element; a handle pivotally mounted on the side wall externally of the firebox and having controlling connection with the door for opening and closing the same; an electrical switch borne by the side wall on which the handle is mounted and operably connected to the depressing member whereby upward pivotal movement of the member closes the switch and return of the member to downward position opens the switch; an energizing circuit for the ignition means including the switch and a source of electrical energy; and lever means interconnecting the handle and the depressing member whereby manipulation of the handle to open the door simultaneously pivots the depressing member upwardly to receive combustible material between said depressing member and the ignition means resulting in closing of the switch and whereby, upon release of the handle, the door is closed by the spring, the depressing member is rested upon the combustible material and pivoted downwardly as the combustible material is consumed until substantially all thereof is consumed at which position of the depressing member the switch is opened.

ANTON H. RIEBSCHLAGER.
